SEWER FLUSHING DEVICE

Filed Feb. 21. 1929

UNITED STATES PATENT OFFICE

LOUIS F. KATONA, OF LOS ANGELES, CALIFORNIA

SEWER-FLUSHING DEVICE

Application filed February 21, 1929. Serial No. 341,598.

This invention relates to an improved type of sewer flushing device and is particularly directed to that general class of devices which automatically function to periodically discharge a predetermined volume of flushing water into a sewer system.

A device of this general character comprises a flushing well having a valved outlet communicating with the sewer conduit to be flushed, said valve being arranged to be automatically opened by mechanism controlled by a predetermined head of water which is permitted to flow into the well at a predetermined preferably slow rate.

15 In a prior Patent, No. 1,642,659, issued September 13, 1927, to C. R. Lion, there is disclosed a device of this general nature having a flushing valve which is operated by a tripping pan or bucket situated in a pit below the floor-board of the well and adapted to receive the overflow from the well until said pan contains a sufficient weight of water to overbalance the weight of the valve so as to open said valve and release the water contained in the well, thus effecting the sewer flushing operation.

20 In devices of this character, the positioning of the pan or bucket in a pit below the floor-board of the well, upon which floor-board the entire mechanism is supported and from which said pan is suspended, has proven to be objectionable in that it is extremely unaccessible for repair or adjustment and for the reason that in order to substitute a new pan for one which is no longer serviceable, it becomes necessary to dismount the entire upper structure and remove the floor-board.

25 It is therefore an object of the present invention to provide a sewer flushing device of the general character referred to, in which all of the mechanism is positioned above the floor-board and is readily accessible for repair or replacement of parts.

30 In the device illustrated in said patent and in other similar devices operating upon the overflow principle, it has been found that the slow overflow brings about a tripping of the mechanism at such a delicate point of balance that the opening and closing movements of the valve are so slow as to at times

render the action quite unreliable and uncertain.

It is therefore a further object of the present invention to substitute for said overflow principle a principle of service water control in which an automatic service valve is controlled by the level of water in the well to direct a full service flow into the operating bucket when said well water reaches a predetermined height, so as to rapidly fill said bucket, and to provide an arrangement by means of which such full service flow into the bucket is extended beyond the point of perfect counterbalance and until the weight of water thus flowing into the bucket appreciably predominates over the opposed weight of the main flushing valve, thus insuring a positive and quick opening of said flushing valve.

35 It is a further object to provide a device of the above character, having a service valve which closes at a water level appreciably less than that required to open said service valve, whereby a full service flow is directed into the operating bucket an appreciable period 70 of time after the flushing valve begins to open.

40 Many thousands of sewer flushing devices of the character disclosed in the said patent to C. R. Lion are now in actual service, particularly in the city and county of Los Angeles, California, and on account of the superior character of the herein described improvements it is very desirous of being able to economically apply such improvements to such flushing devices, therefore such improvements are herein shown as being particularly adaptable for convenient and quick application to the standard type of device illustrated in said patent, and it is an object of the present invention to produce improvements of the above character which may be so combined with such standard structure.

45 Various other objects and advantages will be more fully apparent from the following description of the accompanying drawings which form a part of this disclosure and which illustrate a preferred form of embodiment of the invention.

In the drawings:

Fig. 1 is a vertical section illustrating the flushing device of the present invention as mounted for operation within the well of a sewer system.

Fig. 2 is an enlarged detail section taken on the line 2—2 of Fig. 1.

Fig. 3 is a detailed plan view of the operating bucket and the end of the walking-beam to which it is connected.

In the drawings, 10 designates a well of any particular desired design, having at its top a manhole ring 11 closed by an inner pan 12 and an outer manhole cover 13, preferably located approximately level with the street or ground surface.

Below the floor level of the well 10 is a pit 14 located at the head of a sewer conduit 15, and mounted between the well 10 and the pit 14 is a floor-board 16, preferably formed of wood which has been treated with asphalt or other suitable material to render it watertight, said floor-board being preferably calked in a metal frame 17 which is securely anchored in the masonry of the well.

The floor-board 16 forms a support for the entire mechanism of the device and has a valved opening 18 therein constituting a discharge port establishing direct communication between the well and the sewer conduit 15. An annular tapered valve seat 19 is secured in said opening 18 by screws 20 and cooperating with said seat is a valve 21 having a tapered valve ring 22 preferably formed of rubber and held in an annular groove in said valve by its inherent tension.

Secured to the floor-board by bolts 23 is a tubular standard 24 extending upwardly to a point somewhat above a predetermined high water level and having an overflow opening 25 above said level, the interior of said standard communicating with the pit 14 so that in event of failure of the mechanism to open the flushing valve, the flushing fluid flowing into the well 10 may overflow through the overflow opening 25 and discharge through said standard into the sewer. The standard 24 has laterally and upwardly extending fulcrum arms 26 carrying a fulcrum pin 27 upon which fulcrums a walking-beam 28. To one end of said walking-beam is pivotally connected a valve rod 29 which extends downwardly through the outer end of a guide arm 26^a extending outwardly from the medial portion of the standard 24, said valve rod 29 being connected to the upper end of the bell-valve 21. The opposite end of the walking-beam 28 is forked (as shown in Fig. 3) to provide opposite limb 28^a having aligned depressions 28^b in their upper surfaces.

The mechanism thus far described is of the standard commercial form of the similar parts of the type of device illustrated in the said patent to C. R. Lion and very similar to

those of the device disclosed in the Patent No. 1,256,656, issued February 19, 1918, to G. H. Burns.

The means which I employ for opening the flushing valve 21 includes an operating bucket 30 positioned above the body of flushing water in the well and carried by the forked end of the walking-beam 28. In the particular embodiment herein illustrated the means employed for connecting the bucket 30 to the walking-beam 28 comprises an arm 31 which is preferably made of a flat metal bar having trunnion pins 32 welded to the edges thereof, as indicated at 32^a in Fig. 3, and having a pivot bar 33 welded at its medial portion to the upper outer end of said arm 31 as indicated at 33^a in Fig. 3. This arm 31 has an inner lower end 31^a and the opposite free ends of the pivot bar 33 extend into the bores of pivot blocks 34 which are secured to the respective upper marginal walls 35^a at opposite ends of the bucket 30. The bucket 30 is thus dependably and pivotally supported upon the outer upper end of the arm 31. In assembling the bucket 30 supporting arm 31 upon the forked end of the walking-beam 28, the inner lower end 31^a of the arm 31 is inserted between the limbs 28^a and beneath the arm 28 and the trunnion pins 32 are lowered into the depressions 28^b, as shown in Figs. 1 and 3. By reason of this particular arrangement, the arm 31 and the operating bucket 30 may easily and quickly be applied to the standard form of walking-beam shown, or removed therefrom for repair or replacement.

As shown in Fig. 1, the operating bucket 30 has an opening in its bottom wall and in this opening there is provided a tubular valve seat 43 secured in place by a lock-nut 44 engaging the screw-threaded shank of said seat and clamping against the bottom wall of the bucket. A cap 45 is screwed upon the lower end of said valve seat shank and is provided with a discharge orifice 46 through which the operating rod 47 of a drain valve 48 extends, said rod being considerably smaller in diameter than said discharge orifice, to permit free passage of fluid through said orifice. Said valve rod 47 extends downwardly to within a short distance of the upper surface of the floor-board 16 when the mechanism is in normal condition with the drain valve 48 closed, this slight spacing of the valve rod 47 from the floor-board being for the purpose of allowing a free closing of said valve.

The means which I employ to slowly fill the flushing well and to quickly fill the operating bucket when the well becomes full, will now be described.

A float controlled service valve mechanism includes a valve body 51 suitably secured to the standard by a bracket 55 and having a pressure chamber 52 communicating with a service pipe 53 connected to the city water sys-

tem or other source of water under pressure. A discharge chamber 54 communicates with said pressure chamber 52, through a passage which is controlled by a service valve 55, and 5 with a bucket filling conduit 56 of gooseneck form which extends upwardly a considerable distance and thence downwardly into the upper end of the bucket 30.

The stem 57 of the service valve 55 extends 10 downwardly through the valve body 51 and through a guide bracket 58 formed on said body and between the body 51 and the bracket 58 said valve stem 57 has a reduced portion 59 (see Fig. 2) providing opposed shoulders 15 60. Extending on opposite sides of said reduced portion 50 so as to engage the opposed shoulders 60 are two fork arms 61 of a valve operating lever 62, said arms being pivoted on a pivot pin 63 in the bracket 58 and the 20 lever 62 being provided with a float 64 by means of which the valve 55 is operated. The wall of the pressure chamber 52 has a very small outlet port 65 through which the flushing water is discharged from the service line 25 directly into the well, as indicated in Fig. 1, and the wall of the discharge chamber 54 has a drain port 66, said outlet port 65 being very minute as compared to the size of the service pipe 53 and the filling conduit 56, for instance, 30 where these pipes are one-half inch in size, said port 65 will preferably be the size of a standard number sixty drill.

Describing the operation of the device, it is assumed that the mechanism is in a normal condition with the flushing valve seated 35 and the service water turned on. Under these conditions the pressure of the service water acting upon the upper surface of the closed service valve 55 will tend to hold said valve 40 closed and a very small portion of the service water will slowly discharge from the pressure chamber 52 through the minute port 65, thus slowly filling the main flushing well 10.

In practice a sewer flushing well of ordinary size will have a capacity of about 300 45 gallons of flushing water and the filling jet discharged from the port 65 will be of such small volume that from twenty to twenty-four hours' time will be required in which to 50 fill the flushing well.

As the water level reaches a proper predetermined height, as illustrated in Fig. 1, the water will exert a buoyant force upon the float 64 but until this force is sufficient to overcome the service water pressure exerted upon 55 the upper surface of the closed service valve 55, the float 64 will remain in its normal lower position and become more submerged as the water level rises. When, through such increased submergence, the float has sufficient 60 lifting power, the valve 55 will be opened. However, such opening will not be a slow gradual opening but will be a relatively quick opening since as soon as the valve 55 is 65 "cracked" or just slightly opened to allow a

counterbalancing of pressures, upon opposite sides of the valve, the full elevating force due to the excess submergence of the float required to initially "crack" the valve, is no longer necessary; therefore, the float thus relieved of 70 the majority of its burden, will immediately bob upwardly to seek a higher level, more nearly floating upon the surface of the water, and effect a quick full opening of the service valve. This will be responsible for a corresponding lag in the time of closing of this valve, as will be later referred to.

Upon the opening of the service valve 55 when the well is filled to the desired level, approximately the full service supply (excepting 75 the small amount which continues to flow into the main well through the filling port 65, and a small amount which will, as later described, flow through a safety port 66) will flow through the gooseneck conduit 56 to fill 80 the operating bucket 30.

The flow of service water into the operating bucket 30 will increase the weight hanging upon the outer end of the arm 31 of the walking-beam which connects said bucket 90 with the flushing valve 21 and when this weight overbalances the weight of the flushing valve, the operating bucket will start to descend to correspondingly open the flushing valve.

Contributing to the positive opening of the flushing valve, will be the lag (previously referred to) in the closing of the service valve 55. Of course it will be understood that as soon as the flushing valve starts to open, the 100 flushing water in the well will start to discharge into the pit 14 and sewer 15, through the opening 18, thus causing a lowering of the water level in the well. However, due to the upward bob of the float 64 during the opening of the service valve 55, said valve 55 will not completely close until the water is at a much lower level than that which was required to cause said valve to "crack" and by reason of this lag in the closing of the 105 service valve, the maximum flow of service water into the operating bucket 30 will continue for an appreciable time after the flushing valve starts to open.

The operating bucket 30 retains all of the 110 water which flows into it until said bucket descends a sufficient distance to cause the lower end of the stem 47 of the drain valve 48 to contact with the upper surface of the floor-board 16, whereupon said drain valve 115 will no longer descend with the operating bucket but will remain supported by said rod 47, thus effecting an opening of said drain valve. Upon opening of said drain valve 120 the water contained in the operating bucket 125 will start to drain through the drain port 46; however, the size of this drain port is so proportioned in relation to the size of the well discharge opening 18 and the action of the mechanism, as to insure a complete emptying 130

of the flushing well before sufficient water has drained from the operating bucket 30 to cause a normalizing closing operation of the flushing valve and its associated mechanism.

In the operation of the practical device in actual service, the full opening movement of the flushing valve is effected in a substantially instantaneous manner after the operating bucket is filled and an appreciable time will elapse before the water level in the well will lower sufficiently to effect a closing of the service valve 55 and during this time the service water will continue to flow into the operating bucket at least as fast as it drains through the drain port 46.

The flushing opening 18 is of sufficient size to discharge the 300 gallons of water in the well in about thirty seconds, and this discharge is so fast in relation to the draining of the water from the bucket through the drain port 46 that there is plenty of time for the well to fully discharge its flushing water before the mechanism again starts to normalize.

As previously mentioned, the drain port 66 in the service valve body 52 is a safety feature intended to take care of any ordinary leakage in the service valve; that is, in case of ordinary leakage the water leaking past the closed service valve 55 will drain through the port 66 in preference to flowing upwardly over the gooseneck of the conduit 56, such port 66 being able to take care of valve leakage up to at least a leakage equal to the full draining capacity of such drain port. This draining capacity is sufficient to take care of all ordinary valve leakage; however, if a leakage greater than said capacity occurs, the excess leakage will of course pass over into the operating bucket but this will only cause more frequent operations of the device.

Such a situation will never occur in actual practice since this drain port 66 is approximately one-quarter of an inch in diameter and a valve leakage even approaching such volume would be readily noted and eliminated by repair upon one of the regular periodic inspections to which all municipal sewer flushing devices are subjected.

It has been previously explained how the "lag" in the full closing of the service valve causes the service water to flow into the operating bucket for an appreciable time after the flushing valve 21 starts to open. This is a desirable feature which is further augmented by the provision of the drain opening 66 by reason of the fact that after the service valve 55 is opened and while the operating bucket 30 is being filled, said drain port 66 is discharging water into the well and thus continuing the raising of the water level in the well and the greater submergence of the then stationary float 64, with such resulting delay in the closing of the service valve 55 in relation

to the approximately instantaneous opening of the flushing valve that the full service flow is continued until after the flushing valve is fully opened.

This mechanism provides a means by which standard types of sewer flushing devices, such as disclosed in said patents to Lion and to Burns and in my prior Patent 1,704,437, may be converted into the improved type of device herein disclosed.

In converting any of such standard flushing devices into one of my improved type, all that is required is to disengage the upper end of the bucket rod of such prior devices from the walking-beam thereof, lower the bucket to rest upon the floor of the pit, then disengage said bucket rod from the bucket and withdraw said rod upwardly through the standard and from the well, the bucket 70 remaining in the pit where it will not interfere with the operation of my device. After this is done, the bucket 30 and arm 31 of my improved arrangement may be quickly installed upon the walking-beam 28, as previously explained, and the service valve supporting bracket may be conveniently attached to the side wall of the upper end of the standard 24, as shown in Fig. 1.

From the above description it will be apparent that I have provided an improved sewer flushing device in which the flushing well is slowly filled by a minute flow from the service line and when the flushing water reaches a predetermined level, a float controlled service valve is quickly opened to direct a major service flow directly into the operating bucket until after said bucket and its contained water overbalances and operates the flushing valve, and in which the operating bucket is provided with drain means permitting emptying of said bucket after the flushing well is emptied so as to cause a normalizing of the device.

It will also be apparent that the improved features of the device herein illustrated are particularly adapted for the converting of the old standard types of flushing devices herein referred to, into flushing devices embodying the features and advantages of the present invention.

The bucket draining valve 48 is of particular advantage when the service line pressure is relatively low. However, in cases where the service pressure is relatively high so that the water would flow into the bucket a great deal faster than it could possibly drain through the bucket drain port 46, the bucket drain valve 48 could, if desired, be dispensed with without departing from the broad features of the present invention, and while the particular embodiment illustrated and described herein is fully capable of fulfilling the objects primarily stated, it is to be understood that I do not wish to limit the invention thereto, for it is susceptible of embodiment in va-

rious other forms coming within the full scope of the following claims.

I claim as my invention:

1. In a sewer flushing device, the combination of: a well adapted to contain a body of flushing fluid and having an outlet communicating with a sewer; a flushing valve normally closing said outlet; valve operating means including an actuating bucket adapted to open said valve when said bucket receives a predetermined amount of water; a service water pipe line having a discharge conduit adapted to discharge service water directly into said actuating bucket; a normally closed service valve in said pipe line; and means controlled by the body of flushing fluid in said well and functioning to open said service valve when said flushing fluid reaches a predetermined level and thereby cause said bucket to be filled to effect an opening of the flushing valve.

2. In a sewer flushing device, the combination of: a well adapted to contain a body of flushing fluid and having an outlet communicating with a sewer; a flushing valve normally closing said outlet; valve operating means including an actuating bucket adapted to open said valve when said bucket receives a predetermined amount of water; a service water pipe line having a goose-neck discharge conduit adapted to discharge service water directly into said actuating bucket; a normally closed service valve in said pipe line; and means controlled by the body of flushing fluid in said well and functioning to open said service valve when said flushing fluid reaches a predetermined level and thereby cause said bucket to be filled to effect an opening of the flushing valve, there being a relatively small drain opening in the service pipe line between the service valve and the goose-neck discharge conduit for discharging leakage due to a faulty closing of said service valve and for discharging a portion of said service water directly into the well when the service valve is open.

3. In a sewer flushing device, the combination of: a well adapted to contain a body of flushing fluid and having an outlet communicating with a sewer; a flushing valve normally closing said outlet; valve operating means including an actuating bucket adapted to open said valve when said bucket receives a predetermined amount of water; a service water pipe line having a relatively small port discharging a minor volume of the available service water into said well and a terminal discharge conduit adapted to discharge service water directly into said actuating bucket; a normally closed service valve in said pipe line between said port and said discharge conduit; and means controlled by the body of flushing fluid in said well and functioning to open said service valve when said flushing fluid reaches a predetermined

level and thereby cause a major volume of said service water to flow into and fill said bucket to effect an opening of the flushing valve.

4. In a sewer flushing device, the combination of: a well adapted to contain a body of clear flushing water and having an outlet communicating with a sewer; a flushing valve normally closing said outlet; valve operating means including an actuating bucket adapted to receive only clear water and functioning to open said valve when said bucket receives a predetermined amount of said water; a service water pipe line having a discharge conduit adapted to discharge service water directly into said actuating bucket; a normally closed service valve in said pipe line; and float means controlled by the body of flushing water in said well and functioning to open said service valve when said flushing water reaches a predetermined level and thereby cause said bucket to be filled with service water to effect an opening of the flushing valve.

5. In a sewer flushing device, the combination of: a well adapted to contain a body of flushing fluid and having an outlet communicating with a sewer; a flushing valve normally closing said outlet; valve operating means including an actuating bucket adapted to open said valve when said bucket receives a predetermined amount of water; a service water pipe line having a discharge conduit adapted to discharge service water under pressure directly into said actuating bucket; a normally closed service valve in said pipe line; and float means controlled by the body of flushing fluid in said well and functioning to open said service valve when said flushing fluid reaches a predetermined level and thereby cause said bucket to be filled to effect an opening of the flushing valve, said service valve being arranged to open against the service water pressure, whereby a major submergence of said float is required to overcome the service water pressure and start to open the service valve to effect a counterbalance of pressure on opposite sides of said valve and thus relieve said float of its major burden whereupon said float immediately raises to a point of minor submergence to effect a quick full opening of the service valve.

6. In a sewer flushing device, the combination of: a well adapted to contain a body of flushing fluid and having an outlet communicating with a sewer; a flushing valve normally closing said outlet; valve operating means including an actuating bucket, said valve normally overbalancing the bucket to hold it elevated and the bucket being adapted to overbalance and open said flushing valve when said bucket receives a predetermined amount of water; a service water pipe line having a discharge conduit adapted to dis-

charge service water directly into said actuating bucket; a normally closed service valve in said pipe line; means controlled by the body of flushing fluid in said well and functioning to open said service valve when the flushing fluid reaches a predetermined level and thereby cause said bucket to be filled to overbalance and open the flushing valve and to close said service valve after the flushing valve is opened; and means permitting a relatively slow draining of the actuating bucket after it operates the flushing valve.

7. In a sewer flushing device, the combination of: a well adapted to contain a body of flushing fluid and having an outlet communicating with a sewer; a flushing valve normally closing said outlet; valve operating means including an actuating bucket, said valve normally overbalancing the bucket to hold it elevated and the bucket being adapted to overbalance and open said flushing valve when said bucket receives a predetermined amount of water, said bucket having a restricted drain orifice; a drain valve closing said drain orifice when said bucket is in elevated position; a service water pipe line having a discharge conduit adapted to discharge service water directly into said actuating bucket; a normally closed service valve in said pipe line; means controlled by the body of flushing fluid in said well and functioning to open said service valve when the flushing fluid reaches a predetermined level and thereby cause said bucket to be filled to overbalance and open the flushing valve and to close said service valve after the flushing valve is opened; and means functioning to open said drain valve when the actuating bucket descends, for permitting a relatively slow draining of the actuating bucket after it operates the flushing valve.

8. In a sewer flushing device, the combination of: a well adapted to contain a body of flushing fluid and having an outlet communicating with a sewer; a flushing valve normally closing said outlet; a standard having a fulcrum arm; a walking-beam pivotally supported upon said fulcrum arm, said walking-beam on one side of its fulcrum being connected to said flushing valve and having a forked end on the opposite side of its fulcrum; an operating bucket normally positioned above the maximum water level in said well; and a supporting arm for said bucket detachably engaging the forked end of said walking-beam in a manner to form a substantially rigid extension thereof.

9. In combination: a walking-beam for a sewer flushing device; an operating bucket disposed beyond one end of said walking-beam; and a support for said bucket forming an extension detachably connected to said one end of said walking-beam to increase the length thereof.

65 10. An operating bucket unit for a sewer

flushing device, said unit comprising a bucket, a supporting arm connected to said bucket and having laterally projecting trunnions on its free end portion spaced from the terminal free end of said arm.

70 11. An operating bucket for opening the flushing valve of a sewer flushing device, said bucket having a drain opening in its lower wall surrounded by a valve seat, and a drain valve independent of said flushing valve for closing said drain opening and having a depending valve rod extending through said opening and adapted for engagement by a stationary object when said bucket is lowered.

75 12. An operating bucket for opening the flushing valve of a sewer flushing device, said bucket having a drain opening surrounded by a valve seat, a drain valve independent of said flushing valve for closing said drain opening, and means for opening said drain valve when said bucket is lowered.

80 13. An operating bucket for opening the flushing valve of a sewer flushing device, said bucket having a drain opening, and a drain valve independent of said flushing valve for controlling said drain opening.

85 14. An operating bucket for opening the flushing valve of a sewer flushing device, said bucket having a drain opening, and a drain valve independent of said flushing valve and having a valve rod adapted for engagement by a stationary object to open said drain valve when the bucket is lowered.

90 15. In a sewer flushing device, the combination of: a well adapted to contain a body of flushing fluid and having an outlet communicating with a sewer; a flushing valve normally closing said outlet; an actuating bucket adapted to open said flushing valve and having a drain opening; a drain valve for closing said drain opening; and means for operating said drain valve.

95 16. In a sewer flushing device, the combination of: a flushing valve; a standard; a walking-beam fulcrumed on said standard, said walking-beam on one side of its fulcrum being connected to said flushing valve; an operating bucket; and a supporting arm for said bucket detachably engaging the opposite free end of said walking-beam in a manner to form a substantially rigid extension thereof.

100 17. In a sewer flushing device, the combination of: a well adapted to contain a body of flushing fluid and having an outlet communicating with a sewer; a flushing valve normally closing said outlet; a stationary support; a walking-beam fulcrumed on said support and having one end connected to said valve; an operating bucket normally positioned above the maximum water level in said well; and means for connecting said bucket to the opposite free end of said walking-beam.

115 18. In a sewer flushing device, the combi-

nation of: a well adapted to contain a body of flushing water and having an outlet communicating with a sewer; a flushing valve normally closing said outlet; valve operating means including an actuating bucket adapted to open said valve when said bucket receives a predetermined amount of water, said bucket having a drain opening; a service water pipe line having a discharge conduit adapted to discharge service water directly into said actuating bucket; and means for controlling said drain opening.

19. In a sewer flushing device, the combination of: a well adapted to contain a body of flushing fluid and having an outlet communicating with a sewer; a flushing valve normally closing said outlet; and an actuating bucket adapted to open said flushing valve and normally situated above the maximum fluid level in said well.

20. In a sewer flushing device, the combination of: a well adapted to contain a body of flushing water and having an outlet communicating with a sewer; a flushing valve normally closing said outlet; an actuating bucket adapted to open said flushing valve when said bucket receives a predetermined amount of water; a service water pipe line discharging directly into said actuating bucket, said bucket having a drain opening; and float controlled means for controlling said drain opening.

21. In a sewer flushing device, the combination of: a well adapted to contain a body of flushing water and having an outlet communicating with a sewer; a flushing valve normally closing said outlet; an actuating bucket adapted to open said flushing valve when said bucket receives a predetermined amount of water; and a service water pipe line discharging directly into said actuating bucket.

In testimony whereof, I have hereunto set my hand at Los Angeles, California, this 16th day of February, 1929.

LOUIS F. KATONA.
